Patented Sept. 19, 1922.

Thomas W. Varley Inventor
By his Attorneys
Emery, Booth, Janney & Rooney

UNITED STATES PATENT OFFICE.

THOMAS W. VARLEY, OF NEW YORK, N. Y., ASSIGNOR TO SAFETY CAR HEATING & LIGHTING COMPANY, A CORPORATION OF NEW JERSEY.

ELECTRICAL APPARATUS.

Application filed July 24, 1918. Serial No. 246,432.

To all whom it may concern:

Be it known that I, THOMAS W. VARLEY, a citizen of the United States, and a resident of the city, county, and State of New York, have invented an Improvement in Electrical Apparatus, of which the following is a specification.

This invention relates to electrical apparatus, and with regard to certain more specific features, to apparatus for generating electrical energy for the lighting of railway cars.

Among the objects of the invention may be noted the provision of a method of and apparatus for generating current from a variable-speed source of power with a minimum of complication of parts; and for efficiently lighting railway cars with power obtained from the car axle, with a minimum of expensive regulating devices and other auxiliary apparatus. Other objects will be in part obvious and in part pointed out hereinafter.

The invention accordingly consists in the features of construction, combinations of elements, arrangement of parts, and steps and sequence of steps which will be exemplified in the structure hereinafter described and the scope of the application of which will be indicated in the following claims.

In the accompanying drawing in which is shown one of various possible embodiments of this invention, the figure is a grammatic illustration of a car-lighting system showing my invention.

In electrical systems such as those for furnishing light and power on railway trains, great difficulty has been encountered in furnishing a dependable current at all times and at a reasonable cost. With the increasing extent to which cars are interchanged and routed beyond the tracks of a single railway, it is important that each car be a self-contained unit so far as its lighting is concerned, and the so-called head-end or constant-speed dynamo located at or near the engine and driven by steam therefrom, is not suitable for such cars in view of the lack of standardization of train-lighting voltages and for other causes. It is thus preferable to obtain the power for lighting from the car itself rather than from some other car. The so-called straight storage

systems are of this type and have a limited utility, but are naturally dependent upon charging facilities at more frequent intervals than it is possible or convenient to charge many types of cars, especially Pullman cars. The car battery therefore should be charged en route, with power derived from the car itself, and it is to this type of car-lighting system, sometimes known as the axle system, that the present invention more particularly relates. Axle systems have been found expensive and troublesome in many instances, because of the complication of the parts or the lack of accurate regulation of the generator, or both. As the description progresses, it will be seen that with the apparatus and method of the present invention, there is provided an axle system in which these disadvantages of expense and complication are minimized, without sacrifice of close regulation and automatic operation throughout the various conditions to which such a system may be subjected.

Referring now to the accompanying drawing, there is illustrated at 1 a shaft adapted to be driven from the axle of a railway car by means of suitable transmission, such as a pulley 2 on the shaft 1, connected as by a belt 3 to the pulley 3^a on the axle 3^b of the railway car. The speed of the shaft thus varies with the speed of the car. On this shaft are mounted three sets of armature windings 4, 5, 6, as well as commutators 8, 9. The first and second windings 4, 5, are associated with magnetic circuits 10 and 11, of which parts are indicated in the drawing, and are connected with each other in such a way that the voltage of the winding 4 is opposed by the voltage of the winding 5, so that the net voltage, which may be measured at the brushes 13, 14, is equal to the difference between the voltages of these two windings. The magnetic circuit 10 is excited by the field coil 15, and is normally substantially saturated throughout the ordinary range of operation of the apparatus. The circuit 11 is excited by the field coil 16 and has normally a lower flux density. The field coils 15, 16, may be energized in any suitable way, as from the brushes 18, 19, bearing on the commutator 9 connected to the third or exciter armature winding 6, this latter

winding being associated with the field coil 21 connected in this instance across the brushes 13, 14. Increase of speed of the shaft 1 increases the voltage at the exciter terminals 18, 19, and thereby increases the current in the field coils 15, 16, and increases the flux in the magnetic circuits 10, 11, and increases the voltage in the armature windings 4 and 5. The net generator voltage, however, measured at the brushes 13, 14, is not increased provided the voltages in the windings 4 and 5 have increased equally. Throughout the normal range of speed, that is, from twenty miles per hour up to an average maximum train speed, these voltages in the windings 4 and 5 increase equally with increase of speed, and conversely decrease equally with decrease of speed. This relation between the voltages of the windings 4 and 5 is effected through the dissimilar saturation of the magnetic circuits 10 and 11. The former circuit reaches saturation at a lower speed than the latter, and, as above noted, the characteristic curve for this circuit becomes approximately horizontal at a lower value of field current, and therefore at a lower speed than does the characteristic curve for the circuit 11. This means that with increasing speed the two characteristic curves are separated by decreasing distances, but these decreasing distances, when multiplied by the increasing speed values, to indicate the voltages in the windings 4, 5, produce practically constant products, so that the voltages of the windings 4 and 5 increase in similar amounts with increase in speed, and therefore the net generator voltage, measured at the terminals 13, 14, is maintained substantially constant throughout speed changes. From this it is clear that throughout normal ranges of speed the voltage of the generator is independent of speed changes.

When the generator is connected to a storage battery 24, and to lamps 25, through an automatic switch 26, the operation of the generator effects the charging of the battery when the generator voltage is high enough to close the automatic switch. The generator also at such times preferably supplies current to the lamps 25, through a suitable automatic lamp regulator LR, the details of which form per se no feature of the present invention. When the generator speed is below its normal range, the automatic switch 26 opens, and thus when the train is running slowly or is at rest, the lamps 25 are furnished with current from the battery 24.

Inasmuch as the generator delivers current at substantially constant voltage, the battery is protected from overcharge. In order to protect the battery from an excess of current when the battery is depleted, a

cumulative series coil 28 may be mounted on the field of the exciter in such a way as to add its effect to that of the shunt coil 21, in exciting the armature 6 which furnishes current to the field windings 15, 16. The series coil 28 may be connected to be responsive to a function of the generator current, and as indicated in the drawing, it is preferably connected to receive the total generator current. The effect of current in this series coil 28 is to produce a higher excitation in the magnetic circuits 10, 11, for a given train speed than would otherwise be produced for that speed. In other words, the excitation is what corresponds to a higher speed than the actual speed. The characteristic curves, as above noted, approach each other with increase of speed, so that the vertical distance between them at the higher equivalent speed due to the current in the series coil 28, is less than the vertical distance between the curves at the actual train speed. The generator voltage is thus less than it would otherwise be for such train speed. And this lower voltage reduces the current that would otherwise be delivered by the armatures 4, 5, and protects the battery from excessive current. And this of course applies, no matter what the train speed may actually be, since the characteristic curves approach each other with increase of speed throughout substantially the entire normal range of speeds.

Stated another way, the total field excitation increases with increase of speed. The net field excitation decreases with increase of speed. The net field excitation multiplied by actual speed indicates net generator voltage. Current in the series coil 28 produces abnormally high total field excitations. This means abnormally low net field excitation for that speed. And thus the generator voltage, which is indicated by the product of net field excitation by speed, is made abnormally low by current in the series coil 28. Said series coil thus acts as a current limiting or reducing device, to protect the battery from excessive current.

At excessive speeds such as 80 miles per hour, the saturation curves of the two magnetic circuits are preferably so close together that even when multiplied by the higher speed, the resulting generator voltage is less than enough to deliver full output to the battery. The generator output is thus reduced at these excessive speeds, and if desired the generator voltage may be reduced sufficiently to cause the main switch to open at such speeds.

The operation of this apparatus is such that at all speeds it is in stable equilibrium. That is, upon a tendency to error, such as might be occasioned by change of speed or other variable factor, the apparatus auto-

matically corrects the incipient error and restores equilibrium, and this regardless of the value of the speed at the time.

Upon reversal of the direction of drive, 5 the residual magnetism in the exciter causes its armature 6 to build up with reversed polarity. This reverses the polarity of the field coils 15 and 16 and the magnetic circuits 10 and 11. The polarity of the armature windings 4 and 5 is maintained as before, however, because the reversed direction of drive of these windings, together with the reversed polarity of the magnetic circuits 10 and 11, causes the polarity of 10 the armature windings 4 and 5 and hence the polarity of the generator at its terminals 13, 14, to be the same as before. There is thus no need of a pole-changer or other current-reversing device, either manual or 15 automatic, in the use of this apparatus for railway train-lighting or in other fields where the source of power is subject to reversal in direction of drive.

From the above it will be seen that the 20 several objects of the invention are achieved, and other advantageous results attained.

As many changes could be made in the above construction and many apparently 25 widely different embodiments and variations of this invention could be made without departing from the scope thereof, it is intended that all matter contained in the above description or shown in the accompanying drawings, shall be interpreted as 30 illustrative and not in a limiting sense.

Having thus described my invention, I 35 claim:

1. In apparatus of the class described, in combination, an armature, exciting means 40 therefor comprising a pair of magnetic circuits differentially effective upon said armature, and operating at unequal degrees of saturation, an exciter adapted to excite both of said circuits at said unequal degrees of saturation, a work circuit connected 45 with the armature, and a series coil on the exciter connected in series with at least part of the work circuit, to limit the current therein by raising the strengths of said fields.

2. In apparatus of the class described, in combination, an armature, exciting means therefor comprising a pair of magnetic circuits differentially effective upon said armature, one circuit reaching saturation at a 50 lower field strength than the other circuit, the armature voltage being substantially constant throughout the normal range of speed of the apparatus, an exciter adapted 55 to excite both of said fields, a work circuit connected with the armature, and a series coil on the exciter connected in series with at least part of the work circuit, to limit the current therein by raising the strength of said fields.

3. In apparatus of the class described, in combination, an armature, exciting means therefor comprising a pair of magnetic circuits differentially effective upon said armature, one circuit reaching saturation at 70 a lower field strength than the other circuit, the armature voltage being substantially constant throughout the normal range of speed of the apparatus, but tapering at an abnormally high field current, a work 75 circuit connected with the armatures, and means comprising a coil connected in series with at least part of the work circuit, to limit the current therein by raising the strengths of said fields to said tapering point, upon a tendency to excess current through said coil.

4. In apparatus of the class described, in combination, a variable speed shaft and a pair of armature windings driven thereby, 80 a pair of magnetic circuits associated therewith and operating at unequal degrees of saturation, an exciter driven from said shaft and adapted to furnish increased excitation to said circuits with increase of speed, a 85 load connected to the armature, and a coil on the exciter in series with the generator and at least a part of its load, to increase the excitation to said circuits for limiting the current through said coil.

5. In apparatus of the class described, in combination, a variable speed shaft and a pair of armature windings driven thereby, a pair of magnetic circuits associated therewith and operating at unequal degrees of 90 saturation, an exciter driven from said shaft and adapted to furnish increased excitation to said circuits with increase of speed, a 95 load connected to the armature, and a coil on the exciter in series with the generator and at least a part of its load, to increase the excitation to said circuits for limiting the current through said coil.

6. In apparatus of the class described, in combination, a variable speed shaft and a pair of armature windings driven thereby, a pair of magnetic circuits associated therewith and operating at unequal degrees of 100

saturation, the more saturated circuit being associated with the winding of higher voltage, an exciter driven from said shaft said exciter receiving its excitation from said pair of armature windings and adapted to furnish increased excitation to said circuits with increase of speed, whereby the generator voltage is substantially constant throughout changes in speed, a battery adapted to be charged from said armature, at a speed above a predetermined limit, a relay adapted to automatically disconnect said battery from said armature circuit when the speed falls below said limit and a work circuit connected with the battery.

7. In apparatus of the class described, in combination, an armature having a pair of opposed windings, exciting means therefor comprising a pair of magnetic circuits differentially effective upon said armature, and operating at unequal degrees of saturation, an exciter adapted to excite both of said circuits, a work circuit connected with the armatures, a series coil on the exciter connected in series with at least part of the work circuit to limit the current therein by raising the strength of said fields, and an exciting field on said exciter energized by said opposed armature windings.
8. In apparatus of the class described, in combination, a variable speed shaft and a pair of opposed armature windings driven thereby, a pair of magnetic circuits associated therewith and operated at unequal degrees of saturation, an exciter driven from said shaft and adapted to furnish increased excitation to said circuits with an increase of speed, a load connected to the armature, a coil on the exciter in series with the generator and at least a part of its load to increase the excitation to said circuits for limiting the current through said coil, and an exciting field on said exciter energized by said opposed armature windings.
9. In apparatus of the class described, in combination, an armature having a pair of opposed windings, exciting means therefor comprising a pair of magnetic circuits differentially effective on said armature, one circuit reaching saturation at a lower field strength than the other circuit, the armature voltage being substantially constant throughout the normal range of speed of the apparatus, an exciter adapted to excite both of said fields, a work circuit connected with the armature, a series coil on the exciter connected in series with at least part of the work circuit to limit the current therein by raising the strength of said fields, and an exciting field on said exciter energized by said opposed armature windings.

In testimony whereof, I have signed my name to this specification this 22nd day of July, 1918.

THOMAS W. VARLEY.
